SPRING CLOSING DEVICE

Harold C. Russell, Seattle, Wash., assignor to
W. H. Foster, Seattle, Wash.

Application November 22, 1933, Serial No. 699,247

4 Claims. (Cl. 150—10)

My present invention relates to the art of spring closing pouches and the like and more particularly to a spring closing device.

My spring closure is adapted for use with a pouch or purse where a relatively wide opening is desired. I am aware that spring closures have been used on tobacco pouches and the like where a relatively narrow opening was sufficient. However, when an attempt is made to close a relatively wide opening and relying upon the resiliency of two similar springs which are joined together at their ends, there is not sufficient force in the springs, of reasonable strength, to insure a firm and tight closure. It is to overcome this deficiency of spring closing devices that I have provided my present closure. It consists of novel means whereby a wide closure may be made securely tight and be locked in its closed position against accidental opening and at the same time may be opened by pressure applied to opposite ends by one hand. For sake of simplicity of disclosure I prefer to describe my device as it would appear when applied to a tobacco pouch or purse altho it will be apparent to anyone skilled in this art that there will be many other uses for such a closure.

Other and more specific objects will be apparent from the following description taken in connection with the accompanying drawing, wherein

30 Figure 1 is a perspective view showing a pouch made up after the teachings of my invention.

Figure 2 is a top plan view of such a pouch in its closed but not locked position.

Figure 3 illustrates the manner of opening my purse.

Figure 4 is a top plan view similar to Figure 2 but showing the purse or pouch as it would appear after the springs had exerted their maximum pressure.

40 Figure 5 is an exploded perspective view showing the principal parts making up my present invention.

Figure 6 is a cross sectional view taken in elevation thru the locking members of Figure 1.

45 Figure 7 is a sectional view taken along the line 7—7 of Figure 6.

Figure 8 is a sectional view taken along the line 8—8 of Figure 7.

50 Referring to the drawing, throughout which like reference characters indicate like parts, 10 and 12 designate the main spring members which form with the securing and pivot pins 14, the main closure of my device. Each of the members 10 and 12 are identical in construction and are provided at one end with either a weakening cut-out

as 16 or made of thinner material at one end so as to create the effect of weakening one half of the spring. These weakened portions are oppositely disposed substantially as shown in Figure 5.

The two members 10 and 12 are joined at their ends in some convenient manner as by the turned back or looped ends which are adapted to accommodate the pivot pins 14. Disposed on opposite sides of the longitudinal center of members 10 and 12 is some conventional type of securing means as the nob members 18 and 20. In the illustrations I have shown the ordinary inclined nobs such as form the locking means of the usual coin purse. This is only one form that might be used. Any interlocking lug arrangement would be just as satisfactory excepting it is believed the form shown, lending itself as it does to finger operation might be more desirable.

Disposed on the inner spaces of members 10 and 12 are tapered filling pieces 22 and 24. These taper from nothing at one end to considerable thickness at the end which lies over the weakened portion 16 and 17 of members 10 and 12 respectively. When made up as a pouch or purse, a leather or fabric covering 26 is used which is suitably closed on its three sides and then turned down between the two spring members 10 and 12 and stitched below the lower edge of the same as is indicated in Figures 1 and 7 at 28.

Method of operation

30

In operating my closure when it is applied to a pouch or purse it is probably best accomplished after the showing of Figure 3 in which the thumb and forefinger apply pressure to the opposite ends of spring members 10 and 12. The first action when pressure is applied, due partly to the influence of the filters 22 and 24 which tend to place a slight bow on the weakest portion, is similar to that shown in Figure 2 in which side portions 30 and 32 remain straight whereas the opposite end portion 34 and 36 are bowed outwardly. This has the effect of withdrawing lug or ball member 18 from engagement with member 20 and thus the purse is unlocked without the securing means having to be twisted with the thumb and forefinger of the opposite hand as is customary in most purses.

A continuation of the pressure on each end of the springs causes the two spring members 10 and 12 to separate as indicated in Figure 3. It will be noticed that the two side members do not flex uniformly throughout their ends but at 36 and 34 the curvature is much more pronounced than at 30 and 32. The pouch is now

open so that shredded cut tobacco can be removed therefrom or pipe can be inserted for filling or it is open, and further if it is used as a coin purse, for the ready selection of the desired coin.

- 5   In closing the purse it may be allowed to spring to its closed position as indicated in Figure 4 and then with pressure applied opposite each of the lug members 18 and 20 a snap lock will be effected. It is possible however to lock it easily 10 by keeping some pressure on the ends of the spring so that a position as in Figure 2 is maintained and then by applying a slight amount of pressure as at 38 or 40. This will cause the lugs to engage and a releasing of the end pressure will 15 complete the locking. This latter operation may appear complicated but it is easily accomplished with one hand by just pressing the indicated side portion of the pouch against some firm object.
- 20   The foregoing description and the accompanying drawing are believed to clearly disclose a preferred embodiment of my invention but it will be understood that this disclosure is merely illustrative and that such changes in the invention may be made as are fairly within the scope 25 and spirit of the following claims.

Having thus fully described my invention, what I claim as new and desire to secure by Letters Patent is:—

- 30   1. A pouch closure comprising a pair of plates of resilient metal, hinge joints between adjoining ends of said plates, each of said plates having a substantial slot at one end and said ends lo-

cated at the opposite ends of the closure, and an intermediate snap-fastener including co-acting friction-heads mounted on the plates.

2. A pouch closure comprising a pair of plates of resilient metal substantially uniform in size and shape, each of said plates having an end portion of greater resiliency than the remainder of the plate and said end portions being located at opposite ends of the closure, hinge joints at adjoining ends of said plates and an intermediate snap-fastener including co-acting friction-heads mounted on said plates. 10

3. A pouch closure comprising a pair of substantially parallel, resilient plates having hinged ends, each of said plates having a tapered filling member located at opposite ends of the closure, a snap fastener mounted on each plate between its approximate center and its bowed end, and said fasteners adapted for frictional contact in retaining the closure in closed position. 15

4. A pouch closure comprising a pair of substantially parallel resilient plates having hinged ends, each of said plates having spacing means so disposed between said plates as to cause them to be bowed outwardly from each other, each 20 of said bowed plates having a substantial longitudinal slot located at opposite ends of the closure, a snap fastener mounted on each plate at approximately its center and said fasteners adapted for frictional contact in retaining the 25 closure plates in closed position.

HAROLD C. RUSSELL.
